UNITED STATES PATENT OFFICE.

AMANDA L. SUTTER, OF JERSEY CITY, NEW JERSEY.

HAIR WAVER.

Application filed February 29, 1928. Serial No. 257,802.

This invention relates to a functionally and structurally improved hair curler.

It is an object of the invention to provide a device of this character which will embody 5 an extremely simple and rugged construction capable of being produced at a nominal figure and with a minimum of labor, the device furthermore operating over long periods of time with freedom from difficulty.

10 A further object is that of constructing a hair curler or waver which will efficiently form or maintain a hair wave and which may be worn with practically no discomfort.

15 A still further object is that of providing such a device which may be applied to, or removed from the hair with but little effort and which, when applied, will not become readily and accidentally detached and which, furthermore, when it is in applied position, will 20 not shift out of such position.

With these and further objects in mind reference is had to the attached sheet of drawings in which there is illustrated two practical embodiments of the invention and 25 in which:

Figure 1 is a perspective view showing a curler in closed position;

Figs. 2 and 3 are similar enlarged views of the end portion of the curler, and

30 Fig. 4 is a view similar to Fig. 1, but showing the curler in opened position and illustrating a slightly different construction than that shown in the first figure.

A curler of this nature may be constructed 35 of any desired material such as, for example, strip metal embodying sufficient resiliency to meet the needs of the present device. This strip is bent in a forming operation which may be by means of dies, in order to conform, generally, to the curvature of the scalp and at the same time other portions are provided which will hereinafter be referred to.

Thus, in the annexed drawing, a strip has 40 been shown which is bent upon itself to provide an upper portion 5 and a lower portion 6, the end of the upper portion terminating, preferably, in a hook having an enlarged head 7 and an upwardly curved shank 8 ending in an outwardly curved end 9. The end 45 of the lower portion 6 terminates in a reduced extension or tongue which is preferably curved outwardly, as at 10, to extend at an angle slightly in excess of the angularity of the inwardly curved portion 8 of the hook shank. As a consequence, and as has been 50 shown particularly in Figs. 2 and 3, it will

be patent that the tongue may be readily slipped into an opening 11 formed in what might be termed the apex of the hook shank, so that the parts may be locked against accidental detachment when the device is in applied position.

As shown in all of the views, the upper and lower portions 5-6 are preferably curved throughout their entire length to conform, 65 generally, to the curvature of the scalp and with a view to preventing longitudinal displacement of the curler or waver, the upper portion may, as in Figure 1, be formed, at its time of manufacture, with indentations or bulged portions 12 and, as in Figure 4, if desired, the lower portion 6 may be formed with similar and complementary parts 13.

In using a device of this character the hair is properly arranged, after which, with the outer end of the lower portion detached from the corresponding end of the upper portion the former is inserted below the tress of hair, after which the tongue is inserted through the opening 11, thus securing the device in position. In such position it is obvious that no 75 discomfort will be experienced by the wearer and accidental shifting of the device is precluded by virtue of the fact that a certain amount of the hair tress will be engaged within or between the bulged portion or portions 12-13. The device remains in position for a suitable length of time and results in an artistic and desirable wave being imparted to the hair and when it is desired to remove the appliance this may be accomplished readily by simply withdrawing the tongue from the 80 opening.

Finally, and as will be seen referring to Figure 2, the lower portion 6 may, in advance 95 of the tongue, be formed with an outwardly bulged portion 14 which, in addition to serving to prevent the waver from shifting accidentally, will act as a finger hold whereby the tongue may readily be withdrawn from its position within the opening and the lower portion may be moved sidewise with respect to the upper portion so that the parts clear each other to permit of the ready detachment of the waver when this is desired.

Thus, among others, the several objects aforementioned are achieved, it being intended, however, that numerous changes in construction might be resorted to without in the slightest departing from the spirit of the invention as defined by the claims.

Having described my invention, what I

claim as new and desire to secure by Letters Patent is:—

1. A device of the character described including cooperating upper and lower portions, both curved in the same direction, the end of one of such portions terminating in a hook presenting an enlarged head and an inwardly and outwardly curved shank extending therefrom, a tongue at the free end of the other portion and being outwardly curved and extending through a slot formed in the shank of said hook.

2. A device of the character described including upper and lower portions similarly curved throughout their entire length to extend substantially parallel to each other, a hook at the free end of the upper portion and having an inwardly and outwardly curved shank portion formed with an opening and an outwardly curved tongue at the free end of the lower portion of said device and extending through said opening and bulged portions formed in both the upper and lower portions of said device, said bulged portions being arranged to be complementary to each other.

25 3. A device of the character described in-

cluding upper and lower portions similarly curved throughout their entire length to extend substantially parallel to each other, a hook at the free end of the upper portion and having an inwardly and outwardly curved shank portion formed with an opening and an outwardly curved tongue at the free end of the lower portion of said device and extending through said opening and bulged portions formed in both the upper and lower portions of said device, said bulged portions being arranged to be complementary to each other.

4. A device of the character described including upper and lower portions, a hook at the free end of the upper portion and having an opening formed in its shank, a tongue at the outer end of the lower portion and bent to extend at an angle to the hook-shank and the lower portion being bent at a point to the rear of the tongue to extend outwardly and providing a finger hold.

In testimony whereof I affix my signature.

AMANDA L. SUTTER.
